UNITED STATES PATENT OFFICE.

ELIZABETH ROSE, OF DES MOINES, IOWA.

DESIGN FOR A DOLL.

Application filed May 12, 1922. Serial No. 2,207. Term of patent 3½ years.

To all whom it may concern:

Be it known that I, ELIZABETH Rose, a citizen of the United States of America, residing at Des Moines, in the county of Polk and State of Iowa, have invented a new, original, and ornamental Design for a Doll, of which the following is a specification, reference being had to the accompanying drawing, forming part thereof.

I claim:

The ornamental design for a doll, as shown.

Mrs. ELIZABETH ROSE.
